UNITED STATES PATENT OFFICE.

CONRAD W. FINZEL, OF BRISTOL, ENGLAND.

IMPROVEMENT IN PROCESSES FOR MELTING SUGAR.

Specification forming part of Letters Patent No. 12,719, dated April 17, 1855.

To all whom it may concern:

Be it known that I, CONRAD WILLIAM FINZEL, of Bristol, in the county of Somerset, sugar-refiner, have invented an Improvement in Refining Sugar; and I do hereby declare that the following is a full and exact description thereof, reference being had to the accompanying drawings, and to the figures and letters thereon.

Whereas, it has hitherto been the practice to melt raw sugars by means of steam injected into the pan containing the same, or otherwise in open pans, whereby much fuel is consumed, a large proportion of treacle is formed, while from such melting the sugar becomes colored.

Now, my improvement consists in melting sugars *in vacuo*, whereby a much less quantity of treacle is produced, and the sugars are of a better color than those melted in the ordinary manner.

For the melting of sugars I adapt an ordinary vacuum-pan to my purpose by fitting or providing it with a gage or test apparatus whereby to ascertain the state of the clarification at any time of the operation. A vacuum-pan without any addition might be employed; but then the cover of the man-hole would have to be removed in order to ascertain the state of the working, whereby the vacuum would be destroyed and great loss would be liable to be incurred from the sugar

being drawn over with the air on re-forming the vacuum. By melting sugars *in vacuo* the melting takes place at a much lower temperature than by any of the processes now followed. The sugar is not liable to damage from heat, as it is not long in contact therewith, and a great saving of fuel and time is effected.

In the drawings annexed I have represented a vacuum-pan and test apparatus adapted to the purposes of my invention; but I do not limit myself to any particular form of test-gage or apparatus, as the same may be modified in various ways.

A is the pan; B, the coil for heating the pan; C, test apparatus; D, man-hole.

Figure 2 is a detached view, in section, on an enlarged scale, of the test apparatus.

What I claim is—

The herein-described improvement in refining sugars—that is to say, melting the raw sugar in a vacuum preparatory to the further refining thereof, in the manner and for the purposes as set forth.

In witness whereof I, the said CONRAD WILLIAM FINZEL, have hereunto set my hand this 3d day of November, 1854.

CONRAD WM. FINZEL.
